ELECTRICAL CONNECTOR

Michael Anthony Mattis, Shamokin, Pa.

Application February 7, 1940, Serial No. 317,763

4 Claims. (Cl. 173—340)

The present invention relates to new and useful improvements in connectors particularly for electrical conductors and has for its primary object to provide a device of this character whereby electrical conductors may be quickly and efficiently connected.

Another object of the invention is to eliminate taking the insulation off the wires, also to make a better insulated connection for outside purposes without having to use any other insulation.

Still other objects and advantages of the invention will become apparent from a study of the following detailed description, taken in connection with the accompanying drawing wherein like characters of reference designate corresponding parts throughout the several views and wherein:

Figure 1 is a top plan view of my electrical connector.

Figure 2 is a vertical sectional view, taken substantially on the line 2—2 of Figure 1.

Figure 3 is a top plan view of another form of the device.

Figure 4 is a vertical longitudinal sectional view, taken substantially on the line 4—4 of Figure 3.

Figure 5 is a fragmentary sectional view, taken substantially on the line 5—5 of Figure 4.

Figure 6 is another form of the device.

Figure 7 is a vertical longitudinal sectional view, taken substantially on the line 7—7 of Figure 6.

Figure 8 is a vertical sectional view through still another form of the device.

Referring now to the drawing in detail, it will be seen that the reference numeral 10 designates a substantially rectangular block constructed of insulating material, said block having a groove 11 in its top adjacent one side thereof. The

groove 11 is formed to provide a substantially tapered well 11' having a substantially flat bottom which has an opening 12 therethrough, said opening communicating with a socket 13 in the bottom of the block. Mounted in the body of the

block 10 adjacent the groove 11 is a connector fitting 14 having lead wires 15 and 16 which are embedded in said block 10 with their ends 17 and 18 sharpened and projecting into the well 11'. A wedge member 19 is engaged in the well 11' and is held therein by a bolt 20 which passes through the wedge 19 and has threaded thereon a retaining nut 21 in the socket 13 for drawing the wedge into the well 11' to force the ends of

the wires 22 and 23, which are seated in the

groove 11, to be impaled on the pointed projections 17 and 18.

The form of the device shown in Figures 3, 4 and 5 of the drawing comprises a block 24 having a groove 25 at one side portion thereof, an intermediate portion of which is of greater depth, as at 26, to provide a well for the end portions of conductor wires 27 and 28. The wires 27 and 28 are held in the well 26 through the medium of a wedge 29, said wedge 29 having a recess formed 10 in the upper portion of one side thereof, as at 30, which receives a nut 31 for holding the wedge 29 in the groove 25 through the medium of a screw 32. Thus, the wedge 29 holds the wires 27 and 28 impaled on the sharpened projecting 15 end portions 33' and 34' of the wires 33 and 34 which are connected with the conventional fitting 35.

In the form of the invention shown in Figures 6 and 7 of the drawing the block 36 is constructed to provide for the joining of the ends of pairs of electrical conductors. In this form the block 36 has formed in the top thereof a groove 37 which has its intermediate portion of greater depth to provide a well 37' for receiving the 25 end portions of pairs of wires 38 and 39 which are forced therein through the medium of a wedge 40 and bolt 41 which passes through said wedge 40 and extends through an opening in the bottom of the block 36 to receive a nut 42 and hold the wedge 40 securely in place.

The wedge 40 has extending lengthwise therethrough conductor wires 40' which terminate in projecting points 40'' which penetrate the wires 38 and 39 for providing an electrical connection 35 therebetween.

The form of the invention shown in Figure 8 comprises a shell 43 having a substantially tapered well therein, as at 44, in which the end portions of wires 45 and 46 are impaled and secured by the pointed, projecting end portions 46' of a conductor 46'' in a wedge member 47. The member 47 has a recess 48 formed in one side thereof for receiving a nut 49 which is threaded 45 on a screw 50 for holding the device assembled.

From the foregoing it can readily be seen that an electrical connector of this character may be quickly and easily employed to connect the ends of electric wires with a minimum of effort to 50 secure an efficient connection. This is accomplished by merely placing the ends of the wires in the groove portion of the block in opposed relation and then causing the wedge to force the wires against the impaling conductor and there- 55

by bridge or connect the ends of the electric wires.

Although I have shown and described herein preferred embodiments of my invention, it is to be definitely understood that I do not desire to limit the application of the invention thereto, and any change or changes may be made in the materials and in the structure and arrangement of the several parts, within the spirit of the invention as claimed.

What is claimed is:

1. In a connector, an insulating block having a longitudinal groove therein, the groove being of greater depth through the intermediate portion thereof and having inclined longitudinal ends leading substantially to the surface of the block, conductive pin members projecting into the groove and mounted in the inclined ends of the groove, insulated wires having the ends thereof projecting longitudinally into the groove, and so arranged as to engage the pins, the pins being connected by electrically conductive means, and an insulating wedge having an intermediate portion and inclined ends shaped to correspond to the longitudinal profile of the groove, said wedge holding said pins pierced in said wires and in contact with the conductors thereof, and means to secure said wedge in holding position.

2. In a connector, an insulating block having a longitudinal groove therein, the groove being of greater depth through the intermediate portion thereof and having inclined longitudinal end portions leading to a point adjacent the surface of the block for the reception of the end portions of a pair of insulated conductor wires, conductive pin members mounted in the block and projecting into said end portions of the groove for penetrating the insulated wires, conductive means electrically connecting said pin members, a wedge having an intermediate portion and inclined ends shaped to correspond to the longitudinal profile of the groove, said

wedge being engageable with the conductor wires for holding said wires impaled on the pin members, and means for securing the wedge in operative position.

3. In a device of the character described, an electrical conductor connector comprising a block having a groove formed therein and further having a lateral opening therein, pointed members projecting into said groove for contacting wires therein, conductive means connecting said pointed members, a substantially wedge shaped member having a notch formed in one side thereof mounted in said groove and contacting said wires, a screw threaded member engaged in said lateral opening in said block member, and a nut on said screw threaded member engaged in said notch to hold said wedge and wires in said groove.

4. In a device of the character described, an electrical conductor connector comprising a block having a groove therein, the groove being of greater depth through the intermediate portion thereof and having inclined longitudinal end portions leading to a point adjacent the surface of the block for the reception of the end portions of a pair of insulated conductor wires, said block further having a lateral opening therein, a substantially wedge shaped member having a notch formed in one side thereof mounted in said groove and contacting said insulated conductor wires, a conductor member embedded in said wedge member, a pin member secured to each end of said conductor member embedded in the wedge member and projecting into the groove and in electrical contact with each of the insulated conductor members, a screw threaded member engaged in said lateral opening in said block member, and a nut on said screw threaded member engaged in said notch to hold said wedge and wires in said groove.

MICHAEL ANTHONY MATTIS.
